UNITED STATES PATENT OFFICE

165,509

VACUUM CLOTHES CLEANER

Elizabeth C. Calvin, Leawood, Kans.

Application April 12, 1950, Serial No. 9,152

Term of patent 14 years

(Cl. D9—2)

To all whom it may concern:

Be it known that I, Elizabeth C. Calvin, a citizen of the United States, residing at Leawood, in the county of Johnson and State of Kansas, have invented a new, original, and ornamental Design for a Vacuum Clothes Cleaner, of which the following is a specification, reference being had to the accompanying drawing, forming a part thereof.

In the drawing:

Fig. 1 is a side elevational view of a vacuum clothes cleaner embodying my new design;

Fig. 2 is a front elevational view of the same; and

Fig. 3 is a rear elevational view of the head portion of the cleaner shown in Figs. 1 and 2, the broken line portions being omitted for convenience of illustration.

The essential features of my design reside in those portions shown in full lines.

I claim:

The ornamental design for a vacuum clothes cleaner, substantially as shown and described.

ELIZABETH C. CALVIN.
